UNITED STATES PATENT OFFICE.

FRANK WHEELER, OF MERIDEN, CONNECTICUT.

SYSTEM OF ELECTRIC LOCOMOTION.

SPECIFICATION forming part of Letters Patent No. 431,093, dated July 1, 1890.

Application filed March 27, 1889. Serial No. 304,966. (No model.)

To all whom it may concern:

Be it known that I, FRANK WHEELER, of Meriden, in the county of New Haven and State of Connecticut, have invented new and useful Improvements in Systems of Electric Locomotion; and I do hereby declare the following to be a full, clear, and exact description of said invention, reference being had to the accompanying drawings, and to the letters of reference marked thereon, which form a part of this specification.

My invention relates to improvements in trolley tracks and conductors and trolleys for use in systems of electric locomotion; and my object is to provide a perfectly-insulated conductor and track which will not only support and carry the trolley securely against displacement, but shall be absolutely guarded against loss of current by the crossing and contact of other wires with the consequent danger to animal life, and which will also be perfectly free from the annoyances due to accumulations of snow or ice.

A further object of my invention is to provide an improved trolley for such conductor.

My invention consists in the construction and combination of parts, as hereinafter described, and pointed out in the claims.

In the drawings which accompany and form a part of this specification, Figure 1 is a cross-sectional view of one form of my conductor and track, and showing the trolley also in section. Fig. 2 is a longitudinal section on the line xx of Fig. 1. Fig. 3 is a cross-sectional view of a modification hereinafter referred to. Fig. 4 is a cross-sectional view, partly broken, of the conductor shown in Fig. 1, taken at a point across one of the openings hereinafter referred to.

Similar letters of reference indicate similar parts throughout the several views.

A indicates a tubular conductor, which, in the form shown in cross-section, is substantially inverted-U shaped, but which may be somewhat varied in form without departing from the spirit of my invention. This conductor consists of the arch-shaped portion a , the main wire a' for supporting the arch a and for bringing the current from the source of supply, and the inwardly-projecting portions a^2 , forming the edges of the arch a , and

which I refer to hereinafter as tracks for the purpose of clearness.

The arch a may be of metal, covered on the outside with suitable insulating material, or it may be composed wholly of insulating material, such as wood fiber. If the latter, there will be placed at suitable intervals short conductors for conveying the current from the main wire a' to the tracks a^2 , as shown at a^3 in Fig. 2, and the tracks a^2 will be lined with copper or other suitable conducting material, as shown at a^4 in Fig. 3.

The main wire a' or "backbone" is supported at intervals, by means of eyes a^5 or other suitable swinging connection, to brackets from posts or overhead cross-wires; but it is to be understood that in some instances the tubular conductor may be rigidly supported, so as not to swing.

Suitable openings may be made at intervals in the conductor for the removal or insertion of a trolley, which otherwise could only be inserted or removed from the end of the tube.

In Fig. 4 I show how such openings may be closed by means of the section A' , hinged to the other half of the conductor by the hinge e , thus permitting said section A' to be turned outward for the purpose of removing the trolley through the opening. When said section is dropped back to its place, it is supported in its proper position by means of the stop or brace E , which is secured by bolts e' to the stationary half of the conductor and extends under the main wire a' , and I contemplate making the tubular conductor in sections for convenience in erecting or other purposes.

The trolley, as shown in the drawings, consists of a T-shaped frame B , the upper or horizontal portion of which carries at each end an axle b for the wheels C ; but of course, if desired, the two wheels C could be rigidly secured to the ends of an axle passing through and having a bearing in the said horizontal portion of frame B . The wheels C are formed, as shown, with rounded peripheries; or, in other words, the peripheries in cross-section are convex and on the arc of a circle slightly smaller than that of the tracks a^2 . The trolley may, as is obvious, be provided with an additional wheel or wheels to

run on or in one or both of the tracks a^2 in advance of or behind the two wheels shown. The cord and wire D are for connecting the trolley to a car and for conveying the current thereto.

5 My invention, as shown, is for use in systems where the street-rails are used for the return-current; but it is obvious that by the proper interposition of insulating material 10 one of the tracks a^2 might be used for said return-current.

The backbone-wire may in some cases be omitted, the tubular conductor being supported at suitable intervals by brackets, and 15 the current being supplied along the metallic half-round or concave tracks a^2 . In Fig. 3 I show such an arrangement, and in said figure I also illustrate a divided conductor, the line of division being at the top. In this I make 20 the conductor of a series of sections of any desired length, each section having a flange a^6 at the top, through which a series of short bolts a^7 pass to unite the two halves. The sections are united longitudinally by any suitable means, as by having the ends of two sections on one side meet midway of a section on 25 the other side, and uniting the flanges a^6 by the bolts a^7 . In this modification the backbone-wire may be employed or not. It is obvious 30 that the inwardly-projecting flanges or tracks a^2 may be shaped otherwise than concave—for instance, they may be V-shaped and the trolley-wheels shaped to correspond. One form of my invention contemplates the 35 use of a divided conductor supported by a backbone-wire and with angular trolley-tracks.

Having now described my invention, what I claim, and desire to secure by Letters Patent, is—

1. In a system of electric locomotion, a tubular conductor having a longitudinal opening, and having inwardly-projecting edges on each side of the opening to form trolley-tracks, said tubular conductor being composed mainly of 45 insulating material and having the surface of the tracks of metal, in combination with a trolley having wheels fitted to said tracks, substantially as described.

2. A tubular conductor for systems of electric locomotion, having a longitudinal opening, the edges of said conductor on each side of the opening being curved inwardly and upwardly to form concave tracks for a trolley, said tracks being composed of metal and the 55 sides and top of the conductor being of insulating material, and metallic connections leading from a main conductor to the said tracks, substantially as described.

3. A tubular conductor for systems of electric locomotion, said conductor being divided longitudinally, whereby the two parts thereof may be readily separated or united, substantially as described.

4. The tubular conductor A, consisting of 65 the two partial tubes having tracks a^2 and the flanges a^6 , united by suitable clamps, substantially as described.

In testimony whereof I affix my signature in presence of two subscribing witnesses.

FRANK WHEELER.
